(57) CLAIM

The ornamental design for a wristband, as shown and described.

DESCRIPTION

FIG. 1 is a front perspective view of a wristband showing my new design;

FIG. 2 is a rear perspective view thereof; and,

FIG. 3 is a top plan view, the bottom plan view being a mirror image thereof.

The broken lines shown in the drawings represent portions of the wristband which form no part of the claimed design.

1 Claim, 3 Drawing Sheets

FIG. 3
